UNITED STATES PATENT OFFICE.

AUSTEN M. CURTIS, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed December 8, 1923. Serial No. 679,315.

This invention relates, in general, to the prevention of interference in signaling systems caused by sparking at the contacts of relays, distributors, tuning forks and similar apparatus which operate in the vicinity of amplifying apparatus, and more particularly the prevention of such interference in submarine cable systems.

In submarine cable telegraph operation, in which printing telegraph apparatus is employed, a great deal of difficulty has been experienced due to interference resulting from the operation of nearby apparatus in which electrical circuits are opened and made, causing sparking at the contacts. This disturbance may be the result of sparking occurring in various pieces of apparatus mounted at different locations so that it is very difficult, if not impossible, to eliminate the disturbance by orienting the amplifying apparatus. In certain cases, complete shielding of a submarine cable receiving amplifier, in addition to orienting it with respect to a source of very weak interfering waves, has been found ineffective in preventing interference. The present invention is the result of an investigation to determine the cause of interference under these conditions.

It was found that contact sparks, even when imperceptible by ordinary means, generate trains of free electric waves of sufficient intensity to cause signal distortion, and cover a wide band of frequencies including some so high that a six inch loop of wire is a very high impedance for them. If these waves are allowed to reach the grid of a vacuum tube in any stage of a vacuum tube amplifier they are partly or wholly rectified, and transmitted through the amplifier as low frequency impulses, which are frequently many times stronger than the incoming signals. As the amplifiers in the submarine telegraphy systems under investigation transmitted a band of frequencies varying from about $\frac{1}{2}$ cycle to about 200 cycles, it might be thought that a low pass filter, of the usual type inserted in the line and cutting out frequencies above 200 cycles, would be all that was necessary, but it was found that such a filter is entirely useless.

It is the object of the present invention to protect an amplifier from such disturbances of high frequency. To accomplish this object, there is provided a low pass

filter so mounted with respect to the amplifier that danger of objectionable pick-up is practically eliminated. Briefly stated, the reactive elements of the filter are mounted so close to the amplifier elements that the necessary electrical connections can be made with leads of minimum length.

This and other features of the invention may be more clearly understood by reference to the accompanying drawing, in which Fig. 1 shows diagrammatically a circuit arrangement in accordance with this invention, comprising a low pass filter and a vacuum tube amplifier and Fig. 2 is a view, partly in section, of a vacuum tube amplifier in the socket of which is mounted a condenser, which ordinarily forms one element of the low pass filter.

Referring to the drawing, a non-inductive resistance 5 which may be short-circuited by the closure of switch 6, and an inductance 7 which may be short-circuited by means of switch 8, are connected in series with the grid of the amplifier 9. These elements, together with the condenser 10 connected between the filament and grid of the amplifier, constitute a low pass filter. Both the inductance and the condenser are mounted as close to the vacuum tube amplifier as is possible, and the switch 8 is arranged so that the lead connected to the amplifier side of the inductance is of minimum length. Preferably, the condenser 10 is mounted within the socket 11 of the amplifier in order to eliminate all wiring in so far as it is possible since in some cases it has been found that the interposition of a few inches of wire between the condenser and the grid and filament of the amplifier is almost equivalent to entirely disconnecting the condenser. The condenser, therefore, may be mounted, as shown, in Fig. 2, in which case it is supported by springs 12, 12, which are held rigidly by the terminal screws 13, 13. The springs 12, 12 have right angle portions 14, 14 struck up so as to engage with springs 15, 15 when the amplifier tube is inserted in the socket.

In certain cases it may be found desirable to employ only the inductance coil, and the condenser mounted as described above, in which case the switch 6 may be closed. Under other conditions such an arrangement may produce oscillations, in which case the switch

6 is opened and the resistance 5 serves to dampen the oscillations. Under still other conditions it may be advisable to close switch 8, leaving switch 6 open and thereby eliminating difficulty due to pick-up by the inductance coil 7; which may be the equivalent of a loop antenna. If the inductance coil alone is used with a condenser it may be possible to largely eliminate any disturbance caused by electromagnetic induction by orienting the coil, if but one source of sparking is present. In practice, however, there are usually several sources of sparking that cause disturbance and it is, therefore, not possible to obtain satisfactory operation by orienting alone or by shielding the apparatus. By means of the switches 6 and 8, it is possible to quickly determine the best arrangement to use under any given conditions.

20 A device in accordance with this invention is of considerable importance in connection with submarine cable telegraph operation using amplifiers. Particularly is this the case when operating at high speed, since 25 without such a device it is possible to employ printing telegraph apparatus in submarine cable only by reducing the speed of transmission to a point where "pick-up" is much weaker than the received signals.

30 The invention claimed is:

1. In a low frequency signaling system subject to high frequency extraneous disturbances, an amplifier, a series reactance in the input circuit of said amplifier and mounted immediately adjacent thereto, and a condenser mounted immediately adjacent said amplifier and connected directly between the input terminals thereof without leads of appreciable length.

40 2. In a low frequency signaling system subject to high frequency extraneous disturbances, an amplifier comprising a filament and a grid, terminals therefor, and a condenser having its terminals substan-

tially in alignment with said grid and filament terminals connected between the grid and filament and mounted immediately adjacent said filament and grid terminals.

3. In a low frequency signaling system subject to high frequency extraneous disturbances, an amplifier including a filament and a grid, a mounting socket equipped with terminal springs for said amplifier, and a condenser mounted within the socket and having its terminals connected between the grid and filament springs of said socket.

4. In a submarine cable signal amplifying system subject to high frequency extraneous disturbances an amplifier, a series reactance in the input circuit of said amplifier and mounted immediately adjacent thereto and a condenser mounted immediately adjacent said amplifier and connected directly between the input terminals thereof without leads of appreciable length, said reactance and condenser together constituting a filter for preventing disturbances outside the submarine signaling frequency range from reaching said amplifier.

5. In a low frequency signaling system subject to high frequency extraneous disturbances, a space discharge repeating device including a cathode, an anode and an impedance control element, spaced terminals for said cathode and impedance control elements rigidly connected to said device, an impedance and a condenser in the input circuit of said device and forming a low pass filter, said impedance being mounted immediately adjacent said device, and means for associating said condenser with said spaced terminals without appreciable leads.

In witness whereof, I hereunto subscribe my name this first day of December A. D., 1923.

AUSTEN M. CURTIS.
